UNITED STATES PATENT OFFICE.

EDWIN H. COLPITTS, OF ELIZABETH, NEW JERSEY, ASSIGNOR TO WESTERN ELECTRIC COMPANY, OF CHICAGO, ILLINOIS, A CORPORATION OF ILLINOIS.

ELECTROMAGNETIC COIL.

1,116,020.

Specification of Letters Patent.

Patented Nov. 3, 1914.

Application filed March 25, 1909. Serial No. 485,690.

To all whom it may concern:

Be it known that I, EDWIN H. COLPITTS, a subject of the King of Great Britain, residing at Elizabeth, in the county of Essex and State of New Jersey, have invented a certain new and useful Improvement in Electromagnetic Coils, of which the following is a full, clear, concise, and exact description.

10 This invention relates to electromagnetic coils, and its principal object is to provide an efficient coil whose windings are extremely accurately balanced with substantially no mutual inductance between them.

15 As is well known, it is a common practice to use portions of two grounded telegraph lines as the sides of a metallic telephone circuit. In general this involves the insertion of inductive coils in the telegraph line, and in branches leading therefrom to earth, in a manner well understood by those skilled in the art. Prior to my invention, however, four coils have been used at each telephone station, each coil consisting of a 20 separate unit comprising a core carrying two serially connected windings, one such coil being inserted serially in each telegraph line, and one in each of two grounded branches from said lines. This practice has 25 proved unsatisfactory by reason of the number of coils required, the space occupied thereby, the disturbances produced in said coils by currents traversing adjacent coils, the difficulty of securing a balanced condition of the telephone circuit due to 30 commercial variations in the impedance of the coils, and the difficulty of preserving the balance of said circuit when once established, due to the variations in the impedance of the coils attending changes in intensity of the telegraph currents. By my 35 invention a coil is provided which is free from these objections.

The above and other objects of this invention will be fully set forth in the following specification and claims, and will be more readily understood by reference to the accompanying drawings, in which—

Figure 1 is a vertical sectional view of 50 the coil of my invention removed from the case; Fig. 2 is a top view, partly in section, of said coil; Fig. 3 is a side elevation, partly in section, of said coil mounted on a base;

and Fig. 4 is a circuit diagram showing a mode of connection of the coil in a composite telephone and telegraph system.

The preferred embodiment of my invention consists of a coil comprising two pairs or groups of windings upon a circular or toroidal iron core, the windings of each pair being connected serially and differentially and placed, preferably, in diametrically opposite positions upon said core, and a covering of iron wire laid upon either the peripheral or end surfaces, or upon both said surfaces, concentrically with the axis of the core. With this construction the flux of the opposing magnetic fields, established by currents passing through the differentially connected windings in series, is forced to traverse the air between the core and the outer wire covering or return path, as a result of which, by virtue of the predominance of the air reluctance over that of the iron, the impedance of the windings is rendered practically constant, as will be readily understood by those versed in the electrical art. The iron wire covering, therefore, forms a part of the effective magnetic circuit of each winding. Furthermore, the outer iron wire not only serves to prevent the flux from straying into the field of adjacent apparatus, in which it might develop disturbances, but renders it possible to cover or inclose the structure with a metal case without encountering the transmission losses which would otherwise result from excessive effective resistance caused by the development of eddy currents in the solid metal of said case. The structure just described may, therefore, be used wherever its features have a field, particularly in composite circuits, with distinctly improved results.

In accordance with another feature of this invention, two sets of windings are placed upon a ring core and so arranged with relation to each other that the polar direction of the magnetic lines induced by one set of windings is substantially at right angles to that induced by the other. More specifically these windings may be in two pairs upon a toroidal iron core, each pair comprising two alternate, or diametrically opposite, windings connected serially and differentially. With this construction it is found that if the

pairs of windings be substituted for the pair of coils used heretofore, in either the telegraph lines or in the grounded branches therefrom, the result is a distinct and uniform improvement in operation. This improvement results from the high degree of balance which may be attained as a result of the use of a core common to both pairs, whereby the unbalancing effect of structural variations is reduced to a minimum; in the constancy of balance resulting from the predominance of the reluctance of the air path over that of the iron; and in the absence of internal mutual inductive disturbances, or so called "cross fire", which disturbances are eliminated by the differential relation which the pairs bear to each other. The coil as just described may be embodied in composite circuits with improved results, where space permits of proper separation of the coils, and by virtue of its extreme simplicity and its capability of replacing two coils of the prior art, is an economical form to use. Where, however, it is desirable to mount the coils adjacent one to another, it is preferable to provide against cross talk, cross signaling and eddy current losses by covering either the peripheral or end surfaces, or both said surfaces, with iron wire, as in the case of the first structure described.

Referring to Figs. 1 and 2, showing a coil constructed in accordance with the preferred form of my invention and provided with four windings, 5 is a circular or toroidal core of iron wire wrapped or otherwise covered with suitable insulating material 6. Plates or separators 7 of insulating material are placed upon the core at proper intervals, as, for example, in the structure shown, at intervals of ninety degrees, between which separators the windings 8, 9, 10 and 11 are placed, said windings being wrapped or otherwise covered with suitable insulating material 12. Upon the peripheral surface of the structure just described, and preferably also upon the ends, iron wire 13 may be laid concentrically with the axis of the core, said wire being held in position by some suitable means, as, for example, the cords 14. The alternate, or in the structure shown, the diametrically opposite windings 8 and 9, 10 and 11, are connected serially and differentially and may conveniently be thus joined in the central opening of the core.

Referring to Fig. 3 the coil as described above is placed in an iron case or cover 15 and the vacant space filled with some suitable insulating compound 16 preferably an insulating compound adapted to exclude air, as, for example, a composition of resin and resin oil. The structure thus incased may then be mounted with the open end downward upon a base 17 and secured thereto by screws 18, passing through ears 19. The free ends of the two pairs of windings may be

led out through openings in the base and in slots 20, 21, 22 and 23, to terminals 24, 25, 26 and 27.

Referring to Fig. 4, showing diagrammatically an embodiment of the preferred form of my invention in a composite telephone and telegraph circuit, 28 and 29 are portions of grounded telegraph lines leading from telegraph stations 30 and 31, over which portions it will be assumed that telephone transmission from telephone station 32 is desired. As shown in the diagram, a coil 33 of my invention is directly connected with the telegraph lines, one pair of differentially connected windings, 8 and 9, being inserted serially in the telegraph line 28 from station 30, the other pair of differentially connected windings, 10 and 11, being inserted serially in the telegraph line 29 from station 31. 34 and 35 are condensers connected as usual in grounded branches from the telegraph lines. The telephone set is bridged across the telegraph lines 28 and 29, the usual condensers 36 and 37 being connected in series therewith. Connected with the bridged telephone branch are two grounded branches 38 and 39 leading from each side of the telephone set, said branches including, respectively, the usual condensers 40 and 41, and the differentially connected windings 8 and 9 and 10 and 11, of the coil 42, also of my invention. 43 and 44 are telephone keys and 45 and 46 are sources of telegraph current.

In composite systems of the general type described, equipped with coils constructed in accordance with the preferred form of my invention, the parts of said coils being dimensioned in accordance with well known electrical laws, it is found that telephone currents are practically confined to the metallic circuit comprising portions 28 and 29 and the telephone branches connected thereto, since in any of the four paths to earth at each station, a pair of windings is included, which windings, although differentially connected, possess sufficient inductance to properly oppose the passage of telephone currents. Moreover, by virtue of the use of iron wire, such passage to earth of telephone currents as may occur is not attended with excessive development of eddy currents and consequent energy losses, by reason of the low degree of effective resistance which the pairs of windings possess. Also, since in each coil the windings are upon the same core, coils of this type may readily be manufactured in which the impedances of the pairs of windings are equal, which, as already indicated, is essential to a balanced condition of the telephone circuit. Furthermore, since the flux of the opposing magnetic fields, which the telegraph currents establish, traverses a section of air before reaching the outer iron wire or return 130

path, the desired constancy of impedance and consequent preservation of balance are secured. Since the windings 8 and 9 set up a practically equal field of force at right angles to that set up by 10 and 11, current flow in the telegraph circuits due to mutual induction, or "cross fire" as it is known, is prevented.

- Having described my invention, I claim:
- 10 1. A toroidal coil comprising a core, a plurality of windings consecutively arranged about said core, and means interconnecting pairs of non-adjacent windings in series differentially.
  - 15 2. A toroidal coil comprising a core, four windings consecutively wound on said core,

and means for interconnecting non-adjacent coils differentially in series.

3. A coil comprising a toroidal core, a plurality of windings thereon arranged in 20 mutually non-inductive groups, and a covering of magnetic material forming a part of the effective magnetic circuit of each winding.

In witness whereof, I, hereunto subscribe 25 my name this 24th day of March, A. D., 1909.

EDWIN H. COLPITTS.
